PITCHER

James C. Procter, Marion County, Ind.

Application January 17, 1947, Serial No. 722,596

5 Claims. (Cl. 215—12)

1

This invention relates to what may be generally termed a pitcher and is of that type wherein a two-part housing is employed to permit opening of the housing and the reception therein of a liquid container of a more or less standardized shape such as a milk bottle.

The primary object of the invention is to provide a housing for a neat and attractive exterior appearance, and in which the container may be yieldingly received and held against accidental displacement, and so positioned that only the pouring mouth of the container is externally visible.

A further primary object of the invention is to permit the storage of liquids in the original container within a refrigerator without having to place the housing therein to the end that the container holding the refrigerated liquid may be taken out and placed within the housing for customary use, such as upon the dining room table, and thus avoid necessity of having to change the liquid from the container to some other container, and also to avoid the necessity of handling the container on the table when it becomes wet due to condensation of moisture on its outer surface.

A still further primary object of the invention is to provide a housing wherein one part, particularly the "handle" part will carry the removable container in order to permit the disengagement of the other part of the housing, from that "handle" part. Thus it is permissible to separate one from the other of the two parts of the housing in order to permit easy cleaning of the interior of the housing.

A still further important object of the invention is to provide a positive hinge connection between the two housing parts and at the same time provide such a connection that may be quickly disengaged without the use of tools. These and many other objects and advantages of the invention including the novel construction and assembly of the various elements as embodied in the appended claims will become evident to those versed in the art in the following description of one particular form of invention as now best known to me, and as illustrated in the accompanying drawings.

Fig. 1 is a view in side elevation and partial section of a structure embodying the invention;

Fig. 2, a view in section on the line 2—2 in Fig. 1;

Fig. 3, a view in section on the line 3—3 in Fig. 1;

2

Fig. 4, a view in top plan and partial section; and

Fig. 5, a view in side elevation and partial section with the housing in open position and a bottle partially inserted.

Referring to the drawings, in which like characters indicate like parts throughout the several views, I form a rear housing portion 10. This portion 10 is generally U-shape in cross section with the top and bottom ends curved around toward the plane of the open edges of that portion. Mounted on the inside of this housing 10 is a bracket generally designated by the numeral 11. This bracket 11 has a rear, upturned leg 12 generally triangular in shape in the present form. The upper end of this leg 12 which would constitute the apex of the triangular shape, is perforated to receive therethrough a screw 13 which is passed through the leg 12, through the wall of the housing portion 10 and screw-threadedly engaged in a base portion of a handle 14. The upper end of this handle 14 is fixed against the housing position 10 by means of a second screw 15 passed through the wall of the portion 10 to screw-threadedly engage in an upper end portion of the handle. The leg 12 is not planar in shape but has the lower part 16 turned at right angles to a base 17. This part 16 continues upwardly in the right angle plane for a distance such as one inch, and then curves around rearwardly and upwardly to a diagonal part 18 to come into contact with the inside face of the housing part 10, and continues on upwardly against that face to form the top end portion 19, through which the screw 13 is carried. The central vertical portion of the leg 12 is cut through on the lines 20 and 21, Fig. 3, from the level of the base 17 to the lower end of the part 19. The portion designated by the numeral 22 between these lines 20 and 21, is pressed rearwardly into a shape conforming to the curvature of the inside face of the housing portion 10. Therefore this portion 22 is in intimate contact with that face. In order to prevent rotation of the leg 12 about the screw 13 some means is provided. In the present form, such means consists of a tongue 23 struck rearwardly from the portion 22 to enter into a hole provided through the wall of the housing portion 10, this hole being carried into the handle 14, Fig. 1. The screw 13 serves to hold the tongue 23 and the portion 22 firmly against the housing wall.

The base 17 is continued from the lower end of the part 16 a distance equal approximately to the distance across the base of the container or bottle 24, which is to be carried within the housing.

From the outer end of the base 17, a spring tongue 25 is carried around upwardly and turned outwardly by its upper end. The normal position of the tongue 25 is made to be such that when the bottle 24 is to be seated on the base 17, a rear portion of the bottle will bear against the part 16 and the tongue 25 will be sprung outwardly from its normal position as indicated by the dash lines, Fig. 1, to the solid line position, whereby the bottle 24 is yieldingly urged by the tongue 25 back 10 against the part 16.

The upper end of the housing part 10, designated by the numeral 26, is curved to fit around substantially half of the circumference of the neck of the bottle 24 immediately under its mouth rib 27. In order to reinforce this housing end, the edge of the part 10 is folded or rolled back as indicated in the drawings. Thus, when the bottle 24 is pushed down between the tongue 25 and the part 16, the upper neck portion of the bottle 24 is urged rearwardly into contact with the curved end 26. The bottle 24 may therefore be picked up and carried about when so mounted in the housing 10, by grasping the handle 14. The forward housing section 28 is formed to have any suitable shape which will enclose the forward side of the bottle 24, and engage with the forward edges of the rear housing part 10.

A desirable shape of the forward section 28 is indicated in the drawings wherein the section has a general U-shape in cross section. The upper end of the section 28 is brought in to fit snugly around the forward side of the neck of the bottle 24 to have the end 29 completing the enclosure from the end 26 of the rear part 10. The lower part of section 28 is provided with a base 30 which carries well back under the bottle 24 on the section 28 and part 10 when the two parts are interengaged. Thus, when the section 28 is resting upon its base 30, the section 28 presents a forwardly and upwardly inclining edge 31 on the one side and 32 on the other side to come into contact with the corresponding edges of the rear housing part 10. Preferably a flange 33 extends from each edge 31 and 32 under the edges of the housing part 10 in order to afford better connection therewith.

Now in order to provide not only a positive connection between the housing part 10 and section 28, but to provide for disconnection, a simple structure is embodied operating in the nature of a hinge.

To provide this connecting means, a pin 34 is carried transversely through the section 28 and anchored by its ends to the side walls. Then the upturned legs 35 and 36 of a generally U-shape bracket 37 is positioned to have the web 38 rest against the rear upturned portion 39 of the section 28 which extends upwardly and rearwardly from the base 30, to have ends of the pin 34 pass through those legs to fix them in position. In order to prevent rocking of the bracket 37 in respect to the pin 34, any suitable means may be employed such as is herein shown as consisting of the detents 40 and 41 and pressed outwardly from the web 38 to extend into holes provided in the wall of the section 28.

When the housing part 10 and the section 28 are positioned one against the other in their proper closed relation as indicated in Fig. 1, the underside of the base 17 will be in contact with the top side of pin 34. On each side of base 17 there is provided pin engaging fingers 42 and 43 respectively. Each of these fingers is shaped to slope

downwardly and upwardly to engage elastically under the pin 34 and terminate by an outer end upturned from the underside of the pin to leave a space between that end of the finger and the underside of the base 17 to receive the pin 34 therethrough by slight downward retraction of the fingers. In other words, there is sufficient elasticity provided in these fingers 42 and 43 to keep them engaged with pin 34 and thereby provide a hinge connection around the pin 34 with those fingers. At the same time, this hinge connection may be separated by forcibly pulling one section of the housing apart from the other section, particularly when the two sections are in open position as indicated in Fig. 5.

Further means is provided to retain the two housing parts selectively in closed and open positions as illustrated accordingly in Figs. 1 and 5. The web 38 is centrally formed to have fore and aft spaced apart grooves 44 and 45, Fig. 5, into which may drop the lower end of the elastic tongue 46 which drops centrally downwardly. When the housing parts 10 and 28 are rocked to the closing positions, the lower end of the tongue 46 will be in the rear groove 45 as shown in Fig. 1. Then when the section 28 is rocked forwardly relative to the rear part 10 a sufficient distance to permit removal of the bottle 24, the lower end of tongue 46 will then be in the groove 44. Pulling the rear part on around from the section 28 will permit the tongue 46 to travel forwardly of the web 38 and thus facilitate the separation of the base 17 and its fingers 42 and 43 from the pin 34.

By properly locating the pin 34 and fingers 42 and 43 to the relative positions as indicated in the drawings the lower adjacent ends of the housing part 10 and the forward section 28 will telescope in their open positions as indicated in Fig. 5 without interference and will return to edge contact in the closed positions. The position of the pin 34, in this regard, is slightly back of the vertical central plane through the bottle 24.

Thus it is to be seen that I have provided extremely simple construction for the purposes above indicated and while I have described the structure in one particular form, many structural variations may be employed without departing from the spirit of the invention and I do not want to be limited to that primary form beyond the limitations which may be imposed by the following claims.

I claim:

1. In a pitcher having a removable container, a rear housing part; a front housing part; a base member carried by said rear part, upon which member said container may rest; an abutment at the rear of said base member; an elastic member extending upwardly at the forward side of said base member spaced from said abutment a distance to compressibly receive therebetween a lower portion of said container; said rear housing part being shaped to have its upper end portion fit around an upper rear side portion of said container; said elastic member being formed to contact the forward side of said container to urge its said rear upper portion side substantially against said rear housing upper end portion; a hinge connection between said two housing parts arranged to permit the front housing part to swing relatively from the rear part in fore and aft directions; the upper end of said front housing part being shaped to fit around the front portion of said container and thereby, with the upper end of the rear housing part, complete encirclement of the container to leave an upper

container end exposed, said hinge connection comprising a pin carried by said front housing part, and a finger carried from the rear housing part to extend under and yielding against said pin, said base member being pulled toward the pin by said finger, whereby said housing parts may be separated by forcibly pulling them apart to disengage said finger from said pin.

2. In a pitcher having a removable container, a rear housing part; a front housing part; a base member carried by said rear part, upon which member said container may rest; an abutment at the rear of said base member; an elastic member extending upwardly at the forward side of said base member spaced from said abutment a distance to compressibly receive therebetween a lower portion of said container; said rear housing part being shaped to have its upper end portion fit around an upper rear side portion of said container; said elastic member being formed to contact the forward side of said container to urge its said rear upper portion side substantially against said rear housing upper end portion; a hinge connection between said two housing parts arranged to permit the front housing part to swing relatively from the rear part in fore and aft directions; the upper end of said front housing part being shaped to fit around the front portion of said container and thereby, with the upper end of the rear housing part, complete encirclement of the container to leave an upper container end exposed, said hinge connection comprising a pin carried by said front housing part, and a finger carried from the rear housing part to extend under and yieldingly against said pin, said base member being pulled toward the pin by said finger, whereby said housing parts may be separated by forcibly pulling them apart to disengage said finger from said pin, and stop means yieldingly limiting the rocking apart of said two housing parts.

3. In a pitcher having a removable container, a rear housing part; a front housing part; a base member carried by said rear part, upon which member said container may rest; an abutment at the rear of said base member; an elastic member extending upwardly at the forward side of said base member spaced from said abutment a distance to compressibly receive therebetween a lower portion of said container; said rear housing part being shaped to have its upper end portion fit around an upper rear side portion of said container; said elastic member being formed to contact the forward side of said container to urge its said rear upper portion side substantially against said rear housing upper end portion; a hinge connection between said two housing parts arranged to permit the front housing part to swing relatively from the rear part in fore and aft directions; the upper end of said front housing part being shaped to fit around the front por-

tion of said container and thereby, with the upper end of the rear housing part, complete encirclement of the container to leave an upper container end exposed, said hinge connection comprising a pin carried by said front housing part, and a finger carried from the rear housing part to extend under and yieldingly against said pin, said base member being pulled toward the pin by said finger, whereby said housing parts may be separated by forcibly pulling them apart to disengage said finger from said pin, and stop means yieldingly limiting the rocking apart of said two housing parts, said stop means comprising an elastic finger fixed by one end in relation to said rear housing part and extending by a free end into said front housing part, and said front housing part being a pair of spaced apart grooves in the path of said free end whereby that end may spring from one groove to the other upon rocking of the housing parts.

4. In a pitcher having a removable container, a member forming a rear section of the wall of the pitcher; a container base provided on said section; a container abutment surface at the rear of said base; an elastic tongue spaced above said base; said tongue and abutment being spaced to receive the lower end of the container compressibly therebetween; said wall section having an upper end portion shaped and positioned to fit approximately across the rear side at least of the container when the container is rested on said base; and a front pitcher wall section separate from the said rear section shaped to complete an enclosure around the forward side of the container; and a detachable hinge connection below said base between said two wall sections, and means yieldingly retaining said wall sections selectively in open and closed positions.

5. For a pitcher having a removable container, a container bracket comprising a base; a tongue upturned from the forward edge of the base; a container abutment upturned from the rear of the base; a mounting tongue extending from said base; a down and forwardly turned hinge finger having an upper concave surface adjacent a free end spaced below said base; and a stop tongue extending downwardly and forwardly below said base to an elevation below said finger free end.
